(57) **CLAIM**

The ornamental design for a humidifier, as shown and
described.

DESCRIPTION

FIG. 1 is a perspective view of one embodiment of a
humidifier.

FIG. 2 is a front view of the humidifier of FIG. 1.

FIG. 3 is a rear view of the humidifier of FIG. 1.

FIG. 4 is a left side view of the humidifier of FIG. 1.

FIG. 5 is a right side view of the humidifier of FIG. 1.

FIG. 6 is a top view of the humidifier of FIG. 1; and,

FIG. 7 is a bottom view of the humidifier of FIG. 1.

The broken-line disclosure in the views is for illustrative
purposes only and forms no part of the claimed design.
Further, missing views not shown form no part of the
claimed design.
